UNITED STATES PATENT OFFICE.

EDWARD J. DELEHANTY, OF ALBANY, NEW YORK.

MATERIAL MIXER.

Application filed January 24, 1923. Serial No. 614,588.

To all whom it may concern:

Be it known that I, EDWARD J. DELEHANTY, a citizen of the United States, residing at Albany, in the county of Albany and 5 State of New York, have invented new and useful Improvements in Material Mixers, of which the following is a specification.

My invention relates to mixing machines and more particularly to machines used in 10 mixing concrete or mortar, although it may be advantageously used in mixing grains or other materials.

Its general objects are to provide a mixer which is light and which may be conveniently transported by an individual; which may be cheaply and durably constructed; which may be easily charged and discharged, and which may be easily and 15 efficiently operated by hand. Another object is to provide a mixer into which a charge of materials to be mixed may be dumped at any convenient time and kept separated from a partially or completely 20 mixed charge in the mixing chamber so that the operations of charging and mixing, or 25 charging and discharging, may be carried on simultaneously. Another and further object is to provide a mixer in which the hopper, the mixing chamber, and the discharge 30 chute or trough may be rigidly connected together to form a compact unit which may be tilted upon the mixer shaft to provide 35 dumping. These and other objects and advantages will appear more fully as the description proceeds, reference being had to the accompanying drawings in which—

Fig. 1 is a plan view of my mixer; Fig. 2 is an end elevation, viewed from the charging end; Fig. 3 is a sectional view of 40 the chute on the line 3—3 of Fig. 1; Fig. 4 is a plan view of the mixer shaft; Fig. 5 is a sectional view of the mixer shaft on the line 5—5 of Fig. 4; Fig. 6 is an elevation 45 view of a mixer paddle or agitator, drawn to a somewhat enlarged scale; Fig. 7 is an end view of a paddle or agitator; Fig. 8 is a longitudinal section on the line 8—8 of Fig. 1; and, Fig. 9 is a side elevation of 50 the entire device.

Similar numerals refer to similar parts throughout the several views.

1, represents the hopper into which the materials to be mixed are deposited and in which they are retained until the operator 55 permits them to pass by gravity into the cylindrical mixing chamber, 2, by raising

the gate, 3. Tangential to the bottom of the cylindrical mixing chamber is the bottom, 4, of the chute, 5, which slopes upwardly at an angle to the horizontal except when the mixer is in the discharging position, as shown in the dotted outline in Fig. 8, when it slopes downwardly, as at 4'. By constructing the bottom of the discharge chute tangent to the bottom of the mixing cylinder, it is obvious that I provide a perfectly smooth passageway for the flow of the mixed materials from the mixing cylinder into the chute and that the entire 60 contents of the mixing cylinder can be discharged with less angular movement of the chute than they could if the plane of the bottom of the chute intersected the mixing cylinder. The angles formed between the sides of the chute and the bottom are preferably rounded, beveled, or filleted, as shown at 6, to prevent mortar or concrete from collecting and setting in the otherwise sharp angle.

In the axis of the cylindrical mixing chamber is the hollow shaft, 7, carrying the mixing paddles, 8, which may be of any number and which I prefer to arrange about the shaft as shown in Figs. 1 and 8. The portion, 9, (see Fig. 4) of the shaft, 7, to which the paddles are attached, and which, of course, is within the cylindrical mixing chamber, is square in cross-section. The portions, 10, of the shaft, which extend through the sides of the mixer are round in 70 cross-section. It will be noted that the hopper and chute are rigidly connected by the sides, 11, and the cylindrical portion, 12, to form a single unit supported on the shaft, 7. The end portions, 10, of the shaft, extend into and are supported by the bearings, 13, secured to members, 14, of the frame. This frame may be constructed of any suitable material such as angle irons or other structural shapes having the necessary rigidity and strength, and riveted or otherwise secured together. The end of the frame beneath the chute is supported on the axle, 15, which carries the wheels, 16; and the other end of the frame is supported by the end posts, 17, which are extended 80 downwardly to reach the ground. In order to give the frame structural rigidity and to prevent distortion or flexure, I provide at one end the diagonal cross braces, 18, as 85 well as horizontal members, 19 and 20. The other end of the frame must, of course, be 90 95 100 105 110

open to permit the chute to drop down to the dumping position, as shown by the dotted outline in Fig. 8, and here the side members of the frame are simply connected 5 by the horizontal member, 21, which also acts as a stop for limiting the downward movement of the chute. It is obvious that the member, 21, might be placed at any determined elevation, it being sufficient only 10 that the slope of the bottom of the chute, when resting thereon, be great enough to permit the mixed materials to flow out by gravity. At the cross braced end of the frame I place another horizontal member, 15 22, which acts as a stop, limiting the movement of the mixing unit in the opposite direction. Pivotal secured to the sides of the members, 14, are the handles, 23, which serve somewhat as the handles of a wheelbarrow for raising the rear end of the device and pushing it about on the wheels, 16. When in use, these handles cooperate with the stops, 24, on the end posts, 17; and when not in use, they may be dropped to 25 the position, 23', as shown by the dotted lines in Fig. 9. Keyed, or otherwise secured to the shaft, 7, which projects sufficiently through one of the bearings, 13, for this purpose, is the hand crank, 25, by which 30 the mixer shaft and paddles are rotated.

In order that a worn paddle may be conveniently replaced, I prefer to construct it, as shown in Figs. 6 and 7, of a single piece of metal having a portion, 26, bent to fit 35 around the square shaft and provided with a bolt, 27, for clamping it in position on the shaft. The blade portion, 28, of the paddle is twisted about 45 degrees about its longitudinal axis to give it a partial helicoidal surface and make it propeller-like in 40 form so that it will force the material to one side rather than lift it directly. In mounting the paddles upon the shaft, 7, I prefer to arrange them so that alternate 45 paddles will force the material in opposite directions to obtain a perfect mixture and to prevent the materials from being conveyed to one end of the mixing chamber by reason of continuous impulses in one direction. 50

In order that the shaft, 7, may be readily removed from the mixing chamber, I provide the bearings, 29, which are bolted to the sides, 11, of the mixer. It is obvious 55 that even if the sides were of sufficient thickness to provide a suitable bearing surface, a hole of such size that the squared portion of the shaft could pass freely therethrough would be entirely too large to form 60 a bearing for the round portion of the shaft.

In operation, the materials to be mixed are dumped into the hopper, 1, and are prevented from passing into the mixing chamber by the diaphragm, 30, and the sliding

gate, 3, which is movable in the recesses, 31, formed between the diaphragm, and the angles, 32. The gate, 3, may be raised by pulling up on the hook, 33, and the materials will then drop by gravity into the 70 mixing chamber, 2. When the hook, 33, is released, the gate will drop back to the position shown in Fig. 8, and another charge of materials may be immediately placed in the hopper. The crank is now turned until the materials are sufficiently mixed whereupon, the entire mixer is tilted as a unit about the mixer shaft, 7, as shown by the dotted outline in Fig. 8, to allow the mixed materials to flow down and out the chute. 75 The mixer is then tilted back to its original position and the operation may be repeated. It is obvious, that sufficient space must be provided between the rear end of the mixer and the cross framing to afford clearance 80 for this tilting movement.

While I have shown the bottom of the hopper and mixing cylinder as constructed of two separate pieces suitably attached together and to the bottom of the chute to provide a rigidly connected unit, it is clear that these and other particular forms and features of construction here illustrated may be varied without departing from the scope and spirit of my invention, and I do not wish in any way to limit myself to the particular details herein shown and described. It is important however in constructing my mixer that the hopper, mixing 95 chamber, and chute be made watertight. 100

In practice I have found that No. 18 gauge sheet iron may be satisfactorily used for constructing the main portions of my mixer unit, but that such portions as are subject to considerable abrasion from hard 105 materials such as stone, should be constructed of No. 16 gauge iron.

It will be evident from a consideration of the foregoing that I have provided a light, compact, and rigid mixing device 110 which is particularly useful in laying concrete sidewalks, curbs, gutters, and other like works because the concrete may be dumped from the chute exactly where it is to be placed and the entire mixer may be 115 readily moved as the work progresses.

What I claim is—

1. A mixing machine comprising a cylindrical mixing chamber, a hopper normally closed at the bottom but adapted to discharge into the side of said chamber, means for setting up or cutting off communication between said hopper and chamber, a trough tangential to said chamber along the bottom thereof, and a supporting means for 120 the whole substantially coaxial with the cylindrical chamber; the hopper, trough and mixing chamber being rigidly connected and adapted to rock as a unit about the 125 last mentioned means to discharge the con- 130

tents of the chamber while retaining the contents of the hopper.

2. In a portable machine adapted for mixing concrete, in combination, a hopper; a chute rigidly attached to said hopper for discharging the mixed materials, a mixing chamber intermediate said hopper and chute and communicating with both, means for interrupting the communication between the hopper and the chamber, and supporting means about which the chute may be tipped to discharge the contents of the chamber.

3. In a portable mixing machine adapted for mixing concrete the combination with a hopper normally closed at the bottom, and a chute for discharging the mixed materials, of a segmental mixing cylinder intermediate and attached to both to form a rigid unit, and supporting means about which the unit may be tipped to discharge the contents of the cylinder without spilling the contents of the hopper.

4. In a machine adapted for mixing concrete the combination in rigidly fixed relation with an aggregate receiving and retaining means, of a mixing chamber, means for setting up or cutting off communication between the first mentioned means and said chamber, and pivotally mounted means for discharging the mixed aggregate at a distance from the machine without discharging the contents of the first mentioned means.

5. In a device of the character described in combination, means for receiving a charge

of materials to be mixed, means for conveying the mixed materials from the device to a place of discharge, and means intermediate and communicating with the first two mentioned means for retaining the materials during the mixing operation, the whole being connected to form a rigid unit, together with means for mixing the materials including an axis upon which the unit is tiltable to permit the conveying means to perform its function.

6. In a mixing machine of the character described the combination with a charge receiving means, of a cylindrical mixing chamber rigidly connected thereto and communicating therewith, means for interrupting communication between said first mentioned means and said chamber, a chute having its bottom rigidly tangential to said chamber, for discharging the mixed materials, and means about which the entire device is tilted to provide dumping through said chute.

7. In a device of the class described in combination, a charge receiving hopper, a chute for discharging the mixed materials, a cylindrical mixing chamber tangential to said chute and joining the bottoms of said hopper and chute to form a continuous unit, means for retaining or releasing a charge in said hopper, and mixing means within said chamber including a supporting means for said unit.

EDWARD J. DELEHANTY.
